UNITED STATES PATENT OFFICE.

HANS ADELMANN, OF NEW YORK, N. Y., ASSIGNOR TO HAM BOILER CORPORATION, OF NEW YORK, N. Y., A CORPORATION OF NEW YORK.

OCTAGONAL HAM BOILER.

Application filed March 30, 1925. Serial No. 19,264.

To all whom it may concern:

Be it known that I, HANS ADELMANN, a citizen of the United States, residing at New York city, borough of the Bronx, in 5 the county of Bronx and State of New York, have invented certain new and useful Improvements in Octagonal Ham Boilers, of which the following is a specification.

This invention relates to boilers adapted 10 for the cooking of ham and the like and more particularly to devices of that nature comprising power means for compressing the contents of said boilers, and to mold a ham best shaped for slicing.

15 Among the objects of this invention is to provide a ham boiler having novel means for compressing a ham and the like, said means being arranged in the form of levers to have a high mechanical advantage to 20 permit of the easy compression of the contents of the ham boiler.

Another object of this invention is to 25 provide a ham boiler having novel compression means, and resilient means co-operating therewith to retain the contents of said boiler under pressure, said compression means comprising a plurality of levers having novel co-operation with the boiler and the cover therefor, said levers having 30 co-operation with said resilient means and arranged to permit of a considerable deflection thereof to provide for a high degree of adjustment of the pressure within said receptacle and for the swelling of the contents of the boiler as the cooking progresses.

With the foregoing and other objects in view the invention consists in the combination and arrangement of parts hereinafter described and claimed, and while the invention is not restricted to the exact details 40 of construction disclosed or suggested herein, still for the purpose of illustrating a practical embodiment thereof reference is had to the accompanying drawings in which like reference characters designate the same parts in the several views, and in which—

Figure 1 is a plan view of the ham boiler with parts broken away.

Fig. 2 is a sectional view on the line 2—2 of Fig. 1.

Fig. 3 is a sectional view on the line 3—3 of Fig. 2.

Fig. 4 is a section on the line 4—4 of Fig. 2 showing a detail of the invention.

Fig. 5 is a sectional detail of a modification.

Fig. 6 is a perspective view of a preferred design of ham.

Referring now more particularly to the drawings, 10 represents a receptacle having a flange 11 formed along the outside thereof and preferably at the rim of said receptacle. Said flange serves to suitably stiffen said receptacle and may comprise means such as the offset portions 12 for co-operating with power and locking devices as will be described hereinafter for depressing a cover 13 so as to compress the contents of said receptacle. Said receptacle is of suitable size and form to receive a ham or other contents as desired and is preferably of generally octagonal shape in both longitudinal and transverse section, the corners of the receptacle being eliminated to form the sides 14 and similarly the cover being formed with an inclined flange construction as shown at 13^a so that the form of the ham or the slices of meat packed in the boiler is such as to eliminate such waste as occurs when the corners of the ham are trimmed off in making sandwiches. Said cover is arranged to be movable up and down within the sides of the receptacle to compress the contents thereof as aforesaid.

85 Means for actuating said cover are provided which are mounted thereupon and include a plurality of levers 15, each of which is provided with means for engaging the receptacle at the depressed portions or tongues 12, said means taking preferably the form of the racks 16 which are arranged to pivotally engage said levers as by means of the pins 17. Each of said levers is arranged to movably or pivotally engage said cover at a plurality of points thus providing for 90 the proper equilibrium for said levers. More specifically, said levers engage said cover as beneath the hooks 18 which are secured to said cover by means of the plates 19, and have abutment with said cover at 95 points between said racks and the hooks 18 as by means of the resilient members 20. Said resilient members are mounted upon pins or screws 21 which extend from said levers and engage the cover in a suitable 100 manner as by means of the bosses 22 formed upon the plates 19, said resilient members being arranged to surround said bosses so

as to be reliably held in place thereby. Said pins have movable engagement with said levers, and are slideable within the holes 23 formed therein while the heads of said pins 5 serve to retain said levers and said cover in predetermined spaced relation with each other against the force exerted by the springs 20. Said levers are generally arranged so as to exert the abutment forces 10 at opposite points of said cover so as to secure a proper balance thereof, while said resilient members are located adjacent to said racks to permit of the use of resilient members of a considerable length and for a 15 high deflection thereof to secure the requisite variation in pressure upon the contents of the boiler as the operator may desire. Thus I arrange said levers to extend across said cover and in opposite directions relatively to each other, the ends thereof engaging said hooks being preferably in proximity to said cover while the opposite ends of said levers are in spaced relation thereto. This arrangement provides, moreover, for a high leverage 20 to permit of easy compression of the boiler contents. More specifically, the normal mode of operation is for the operator to first engage a rack with the receptacle at a predetermined tooth, and then to depress the 25 free end of the lever to engage the same with its co-operating hook, a considerable leverage being thus provided, the fulcrum being at the rack. When both levers are so engaged the cover is in proper balanced position 30 and is movable upward against the force of the springs as the boiler contents expand in course of cooking, the levers providing at their pivotal connections for ample movement. Said levers are also mounted 35 in close proximity to each other and are preferably offset slightly as shown at 24 to permit the racks to be arranged centrally of said receptacle. In a similar manner, the resilient members are arranged along a central longitudinal axis of the receptacle, while the free ends of the levers are tapered or offset slightly at 25 to form tongues to engage readily beneath the hooks 18. The 40 total offset, however, as between said tongues and the central axis of the receptacle is kept at a minimum to prevent binding and to insure a smooth operation of said levers.

As a modification of the arrangement of the levers, I show in Fig. 5 a plurality of levers 15^a having fixed pivotal engagement with the cover of the receptacle and similarly actuated by a resilient member. Said fixed pivotal engagement is provided as by 45 means of a connection by means of a pin 26 to an anchor member 27 which is arranged to support the boss 22 and is secured to the cover of the receptacle. Thus a plurality of fixed engagement means is provided 50 between the cover and each lever, one be-

ing at the pins 26 and the other at the pins 21, the levers being operative by being depressed directly at said rack by manual or power driven means.

Whereas in Fig. 2 the power is applied at 70 the longer ends of the lever, in the arrangement of Fig. 5, the power is applied more directly over the rack ends of the levers and so close to the point of application of the power to the springs. Force applied to 75 the rack or outer end of either lever will tend to cause such lever to tilt or pivot with relation to the hook 18 as a pivot. It will also be noted that in each arrangement 80 the levers cross each other between the ends of the boiler and extended practically from one end to the other thereof and so form a means for giving readily and easily suitable compression to the structure, and yet provide a means along with the racks or hooks 85 for cooking and handling purposes.

The form of ham or other commodity molded and cooked in this boiler, shown at H in Fig. 6, is peculiarly well suited for the purpose under consideration, especially for 90 the making of sandwiches, in which practice it is always desirable from every viewpoint for the meat, irrespective of the thickness in which it may be sliced, to be so formed as to substantially fill the space between the slices of bread and with practically no overlap or projection from the bread. It is my purpose, therefore, in the practice of this particular invention to form 95 or mold a meat product of the most suitable form or size as to meet these requirements as well as to present the most pleasing appearance in the piece before being sliced. Furthermore, in the present extensively 100 practiced art of making and boiling hams it is customary to not only remove the 105 bones, but also the skin, in which condition the meat and fat are left in a substantially fluid state adapting the mass to be formed according to the design indicated so that the hock or knuckle end of the ham, which heretofore has been a subject of considerable 110 waste, involving a problem in economy both to the ham maker and the dealer, is now utilized to good advantage by becoming suitably intermingled with the more fleshy portions of the ham as a result of the formation 115 in this new boiler. It will be noted also that every particle of the mass may be formed into regular slices without a particle of waste and that every slice throughout the ham between the extreme end slices is octagonal in shape.

I claim:

1. In a ham boiler, the combination with a 125 receptacle and a cover therefor, of means for depressing said cover to bear down upon the contents of said receptacle and to lock said cover in depressed position, said means comprising a pair of levers extending across 130

5 said cover, racks pivoted to an end of each of said levers and arranged to adjustably engage said receptacle at opposite points thereof, each of said levers having pivotal engagement at the other end thereof with said cover and at a point opposite to the location of its rack, resilient abutment means being provided for each lever at a point between the ends thereof to resiliently 10 depress said cover according to the adjustment of said racks, said resilient means being arranged in proximity to said racks and remotely from the opposite ends of said levers so as to provide space for a considerable deflection of said resilient means when said racks are adjusted.

15 2. In a ham boiler, the combination with a receptacle and a cover therefor, of means for securing said cover to said receptacle comprising a pair of levers extending across said cover side by side, a pair of pivot means near the ends of said cover co-operating individually with said levers, and fastening means at both ends of each lever, 20 said fastening means having freely detachable engagement with said receptacle at one end of a lever and similar engagement with said cover at the other end of the lever.

25 3. In a ham boiler, the combination with a receptacle and a cover therefor, of means for securing said cover to said receptacle comprising a pair of levers extending across

30 said cover side by side and disposed symmetrically about the central vertical plane of the boiler, upstanding guide means being provided upon the cover near the ends thereof co-operating individually with said levers to retain the same in movable engagement with said cover, resilient means at said guide means providing individual 35 pivot means for said levers, and means at one end of both levers engaging the receptacle at opposite ends thereof and at the other ends of said levers for engaging said cover, said levers being movable downward 40 along the guide means to compress the resilient means and depress the cover, said levers being likewise movable about said guide means in a horizontal direction to be attached or detached from said cover for 45 releasing the same or for locking it down.

4. The combination as in claim 3 wherein said guide means are located about the longitudinal central plane of the boiler and the adjacent portions of said levers are 50 mounted symmetrically thereon, each lever being offset to one side of said plane and extending thence into engagement with said cover at a side of the guide means co-operating with the other lever. 55

In testimony whereof I affix my signature.

HANS ADELMANN.
